UNITED STATES PATENT OFFICE.

WILLIAM H. MORRIS, OF BELLAIRE, OHIO.

VALVE.

Application filed November 26, 1920. Serial No. 426,527.

To all whom it may concern:

Be it known that I, WILLIAM H. MORRIS, a citizen of the United States, and resident of Bellaire, in the county of Belmont and State 5 of Ohio, have invented a new and useful Improvement in Valves; and I do hereby declare the following to be a full, clear, and exact description thereof.

My invention relates to valves for liquid receptacles such as gasoline tanks and it has for its object to provide a tank valve of simple and improved construction, whereby a reserve supply of liquid is made available for use when the main supply in the tank 15 has been exhausted.

In the accompanying drawing, Fig. 1 is a vertical sectional view of a portion of a gasoline tank having an improved reserve supply valve constructed in accordance with 20 my invention; and Fig. 2 is a vertical sectional view similar to Fig. 1 showing the valve in position to utilize the reserve supply of gasoline.

In the drawing, the numeral 2 designates 25 a gasoline tank which may suitably be the ordinary feed tank of an automobile. In the bottom of the tank 2 is formed a boss 3 which is screw-threaded to receive the threaded upper end of a fixed T-shaped 30 outlet tube 4 having a branch connection 5 screw-threaded at 6 for attachment to the usual gasoline supply line. The lower end of the outlet tube 4 is screw-threaded at 7 to receive a cap 8 within which is a suitable 35 packing ring 9 which prevents the escape of liquid from the lower end of the tube 4.

A tube 10 of proper diameter to fit tightly but slidably within the fixed tube 4 extends through the tube 4 and into the tank 2, and 40 carries at its lower end a stop cock 11. The tube 10 also carries a stop member 12, suitably a disc or washer, which limits the downward movement of the tube 10. Just 45 below the stop member 12 the tube 10 is provided with an opening 13 and below the opening 13 is another and longer opening 14 which communicates with the branch connection 5. It will be observed that the opening 14 communicates with the branch 5 in all 50 positions of the tube 10.

In the normal operation of the gasoline tank the valve is in the position shown in in Fig. 1. The gasoline enters the upper end of the tube 10 and thence passes through 55 the opening 14 and the branch 5. The por-

tion of the tube 10 below the opening 14 serves as a trap for sediment, which may be removed from time to time through the stop cock 11. The stop cock also provides convenient means for drawing off a part or 60 all of the gasoline from the tank.

When the level of the gasoline in the tank descends to the level of the upper end of the tube 10 it will cease to flow and warning will thus be given that the tank is 65 nearly empty. In order to make use of the reserve supply of gasoline the tube 10 is pushed up into the position shown in Fig. 2. The gasoline then enters through the opening 13 and passes out through the opening 14 and the branch 5 as before, the elongated shape of the opening 14, keeping the tube in communication with the branch 5.

As shown, the opening 13 in the upper position of the valve as shown in Fig. 2, is 75 slightly above the bottom of the tank 2. Thus when the reserve supply of gasoline is almost exhausted the flow will again stop, but a small amount of gasoline will still remain in the tank and may be made available by pulling out the tube 10 slightly, so as to lower the opening 13 without drawing it down below the bottom of the tank. I thus provide for warning the driver of the automobile at two separate times of the fact that 85 his tank is nearly empty.

While I have shown and described a preferred embodiment of my invention, it is to be understood that various changes may be made and that my invention is limited 90 only by the scope of the appended claims.

I claim as my invention:—

1. A valve for liquid receptacles comprising a tubular member having a lateral outlet, a tube mounted slidably within the said tubular member and having both ends extending beyond the said member, and means for limiting the sliding movement of the said inner tube, the said inner tube being provided with two openings, one of the said 100 openings being in constant communication with the said lateral outlet and the other opening being beyond the said tubular member in one position of the said inner tube and being enclosed within the said member in 105 another position of the said inner tube.

2. A valve for liquid receptacles comprising a tank, a tubular member adapted to be screw-threaded into the bottom of a tank and provided with a lateral outlet, a tube 110

slidably received within the said member, a stop for limiting the downward movement of the said inner tube, and a stop cock secured to the lower end of the said inner tube, the said inner tube being provided with two openings, one of the said openings being disposed adjacent to the said said stop member and the other said opening being disposed below the said first 10 named opening and in communication with the said lateral outlet.

3. A valve for liquid receptacles comprising a tubular member adapted to be screw-threaded into the bottom of a tank and 15 provided with a lateral outlet, a tube slidably disposed within the said member, a cap surrounding the lower end of the said member tube, packing material enclosed within the said cap and surrounding the said inner tube, a stop member for limiting the downward movement of the said inner tube, and a stop cock secured to the lower end of the 20 said inner tube, the said inner tube being

provided with two openings, one of the said openings being disposed adjacent to the 25 said stop member and the other said opening being of elongated form and in constant communication with the said branch outlet.

4. The combination with a gasoline tank, and a chambered supply pipe coupling connected into and communicating with the bottom of said tank, of a supply pipe section mounted in and adjustable endwise through said coupling with its upper end 30 projecting into said tank and its lower end 35 extending below said coupling, said supply pipe section having a lateral port communicating with the chamber of said coupling, and a drain valve in the lower end of said supply pipe section. 40

In testimony whereof, I the said WILLIAM H. MORRIS have hereunto set my hand.

WILLIAM H. MORRIS.
